UNITED STATES PATENT OFFICE

JOHN M. AUFIERO, OF BROOKLYN, NEW YORK, ASSIGNOR TO E. A. LABORATORIES, INC.,
OF BROOKLYN, NEW YORK, A CORPORATION OF NEW YORK

DESIGN FOR A COVER PLATE FOR A SIGNAL DEVICE OR SIMILAR ARTICLE

Application filed October 24, 1930. Serial No. 37,370. Term of patent 14 years.

To all whom it may concern:

Be it known that I, JOHN M. AUFIERO, a citizen of the United States, residing at Brooklyn, in the county of Kings and State of New York, have invented a new, original, and ornamental Design for a Cover Plate for a Signal Device or Similar Article, of which the following is a specification, reference being had to the accompanying drawing, forming a part thereof, wherein—

Fig. 1 is a face view; and

Fig. 2 is a transverse sectional view taken along the lines 2—2 and in the direction of the arrows of Fig. 1.

I claim:

The ornamental design for a cover plate for a signal device or similar article as shown.

JOHN M. AUFIERO.
